(57) **CLAIM**

The ornamental design for an electronic device, as shown and described.

DESCRIPTION

FIG. 1 is a perspective view of an electronic device, showing the new design illustrated in a closed configuration;

FIG. 2 is a perspective view thereof illustrated in an open configuration;

FIG. 3 is a top plan view of the device as illustrated in FIG. 2;

FIG. 4 is a bottom plan view of the device as illustrated in FIG. 2;

FIG. 5 is a rear elevational view of the device as illustrated in FIG. 2;

FIG. 6 is a front elevational view of the device as illustrated in FIG. 2;

FIG. 7 is a side elevational view of the device as illustrated in FIG. 2 as viewed from the right side; and,

FIG. 8 is an opposite side elevational view of the device as illustrated in FIG. 2 as viewed from the left side.

The broken lines in the figures illustrate portions of the electronic device that form no part of the claimed design. The shading is provided merely to represent contours of the design and does not connote the character of the surfaces such as any specific texture, material, gloss, translucence, transparency, surface treatment, or surface decoration.
